[57] CLAIM

The ornamental design for a computer disc container,
substantially as shown and described.

DESCRIPTION

FIG. 1 is a perspective view of a computer disc container showing our new design;

FIG. 2 is a perspective view of the lower portion;

FIG. 3 is a top plan view of FIG. 1;

FIG. 4 is a bottom plan view of FIG. 1;

FIG. 5 is a front elevational view thereof;

FIG. 6 is a side elevational view thereof;

FIG. 7 is a cross-sectional view taken through the center of FIG. 5;

FIG. 8 is a top plan view showing an alternate embodiment of our new design;

FIG. 9 is a bottom plan view of the alternate embodiment of FIG. 8;

FIG. 10 is a cross-sectional view similar to FIG. 5 but of the alternate embodiment of FIGS. 8 and 9.
